UNITED STATES PATENT OFFICE.

WILLIAM REID, OF NEW YORK, N. Y.

IMPROVEMENT IN TEMPORARY BINDERS.

Specification forming part of Letters Patent No. 149,790, dated April 14, 1874; application filed February 2, 1874.

To all whom it may concern:

Be it known that I, WILLIAM REID, of the city, county, and State of New York, have invented a new and Improved Temporary Binder; and that the following is a full, clear, and exact description of the same, reference being had to the accompanying drawings and to the letters of reference marked thereon, making a part of this specification.

This invention has for its object the construction of files for pamphlets and papers; and the invention consists in a pamphlet and paper file with an adjustable automatic back, combined with tie-rods, stitching-cords, and needles, constructed and arranged in the manner hereinafter fully described.

By my invention a ready file or binder is produced that will enable the user to readily file his pamphlets and papers, so that they can be easily referred to, and at the same time be in such a compact state as to possess all the advantages of a regularly-bound book.

In the accompanying sheet of drawings, Figure 1 represents a plan or top view of my file or binder open; Fig. 2, an edge view of same; and Fig. 3, an end view, showing the file or binder closed.

Similar letters of reference indicate like parts in the several figures.

A represents the sides of my file or binder. These sides may be constructed of the ordinary binder's board, and covered with cloth, leather, or any suitable material. To one of the sides A is affixed a flexible back, a, and to the other of said sides is affixed a wire or rod, B, and also a rod or wire, C. The wire B has formed in it two eyes, c c. To the first-mentioned side A is secured a rod, or wire, e. This last-mentioned rod is bound and covered onto the side so as not to be visible. The rods B and C are so affixed as to be visible on the inner side of the side A. Onto the rod C are secured three elastic straps, f f f. The lower

ends of the upper and lower ones of these straps are secured to the inner edge of the flexible back a by passing around a wire fastened to the edge of said back. The center one of said straps f has affixed to it a catch or hook, g.

My file or binder being constructed substantially as above described, it is operated or used in the following manner: Stitching-cords h, one end of each being secured to the wire e, and their other ends being threaded through needles i i, (or they may be formed into loops and be attached to the wire e and the needles i i, as shown in Fig. 1,) are passed through the back of pamphlets or papers D, and through the holes or eyes c c in the wire B, and thence to the fastener or hook g, where they are held in position, confining the pamphlet or paper snugly against the wire B and securely within the sides A. As the number of pamphlets or papers filed or bound increases, the elastic straps f f permit the flexible back a to be drawn out from the inner side of the boards A, so that this back readily accommodates its width to the number of pamphlets filed within the sides, the upper and lower elastics f f keeping the back always in position, and the central elastic f adjusting or rendering adjustable the stitching-cords h h.

I am aware that temporary binders have been made with extension-backs; and I do not claim this broadly; but

Having thus described my invention, what I claim as new, and desire to secure by Letters Patent, is—

A temporary binder provided with boards A and flexible extension-back a, rendered automatically adjustable by elastic straps f, arranged and operating substantially as shown and described.
